(57) **CLAIM**

The ornamental design for a ceiling fan with light, as shown and described.

DESCRIPTION

FIG. 1 is a top, front, right side perspective view of a ceiling fan with light, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion 9 in FIG. 2; and,

FIG. 10 is a bottom, right side perspective view of the ceiling fan with light.

The broken line circle and lead line in FIGS. 2 and 9 represent the boundary of the enlarged view. All other broken lines illustrate portions of the ceiling fan with light. The broken lines form no part of the claimed design.
